UNITED STATES PATENT OFFICE.

SAMUEL K. DENNIS, OF CHICAGO, ILLINOIS, ASSIGNOR TO INTERNATIONAL HARVESTER COMPANY, A CORPORATION OF NEW JERSEY.

TRUCK ATTACHMENT FOR SEEDERS.

No. 800,991.

Specification of Letters Patent.

Patented Oct. 3, 1905.

Application filed August 5, 1905. Serial No. 272,872.

To all whom it may concern:

Be it known that I, SAMUEL K. DENNIS, a citizen of the United States, residing at Chicago, in the county of Cook and State of Illinois, have invented certain new and useful Improvements in Truck Attachments for Seeders, of which the following is a specification, reference being had to the accompanying drawings, forming a part thereof.

10 My invention relates to seeders, and particularly to a truck attachment for machines of that class whereby the machine may be so mounted that it will readily pass through a narrow opening or may be drawn through 15 narrow lanes or roads when being transported to or from a field; and it consists in providing a truck-axle secured in a transverse position intermediate the ends of the seed-hopper and adapted to receive the regular ground-wheels 20 of the machine; also, in providing means whereby the tongue may be transferred from the front of the machine to one of the regular axes of the wheels.

The invention further consists in the novel 25 construction and combination of the several parts, as illustrated by the accompanying drawings, in which—

Figure 1 represents a partial plan view of a seeder, hopper, and truck attachment embodying my invention. Fig. 2 is a cross-section on line A B of Fig. 1. Fig. 3 is a sectional detail of the tongue-socket. Fig. 4 is a cross-section of the truck-axle and supporting-bracket on line C D of Fig. 2. Fig. 5 is 35 a side elevation of a part of the machine, showing the manner of attaching the truck and pole for transportation purposes; and Fig. 6 is a sectional detail of a part of the tongue-attaching means.

40 Similar reference characters denote similar parts throughout the several views.

1 represents the seed-hopper, mounted upon the longitudinally-arranged frame members 2 and 3 and provided with the usual stub-axes 45 at each end thereof adapted to have the ground-wheels journaled thereon, one of which axles being shown by dotted lines in Fig. 5. A bracket-piece 4 is secured to the frame members 2 and 3 at the center portion thereof and 50 to the bottom of the hopper and is provided with a forwardly-projecting tubular portion 5, adapted to enter the rear end of a socket-piece 6, secured to the rear end of a tongue-piece 7, the socket-piece being secured to the bracket

by means of a pin 8 passing through openings 55 in the two members.

The tongue may be of the usual length where two draft-animals are used and suitably supported laterally by braces extending to the associated frame members in any approved 60 form, or a thill attachment may be used, as represented in the drawings, the only essential being to provide a ready means for attachment and detachment of the parts.

9 is a truck-axle having the journal portions 65 10 and 11, adapted to receive the ground-wheels of the seeder in the same manner as the stub-axes at the ends of the hopper and which are secured thereon by the usual keys passing through openings in the outer ends of the 70 journals. The axle is provided with a downwardly-bent portion 12, disposed in a horizontal plane and embraced by the depending sides 13 and 14 of a depending bracket 15, secured to the frame members 2 and 3 by means of 75 the upstanding ears 16 and 17, in which position it is secured by means of the bolt 18.

The socket-piece 6 is provided with a transverse opening 19 near its outer end that registers with a corresponding opening 20 through 80 the tubular portion 5 in a manner to receive the securing means when in position for the regular operation of the machine, and when the tongue attachment is transposed to its position on one of the stub-axes of the seeder 85 there is an additional opening 21, vertically disposed therethrough, that will register with the opening at the other end of the axle-journal in a manner to receive the securing-pin, as shown in Fig. 5. 90

What I claim as my invention, and desire to secure by Letters Patent, is—

1. In a truck attachment for seeders, the combination of a hopper frame members upon which said hopper is mounted, ground-wheels, 95 journals for said ground-wheels longitudinally disposed relative to the hopper, a truck-axle mounted in a transverse position relative to the hopper and intermediate its ends, said truck-axle having a downwardly-bent middle 100 portion secured to said frame members and journal portions at opposite ends thereof and above the plane of said bent portion adapted to receive said ground-wheels.

2. In a truck attachment for seeders, the combination of a frame, a hopper mounted on said frame, stub-axes mounted at the ends of said frame and extending longitudinally rela-

- tive to said hopper, a truck-axle supported by the frame and extending upon opposite sides thereof at right angles to the stub-axles, said truck-axle having a downwardly-bent 5 middle portion secured to said frame and journals at its opposite ends above the plane of the bent portion and ground-wheels adapted to be mounted either on said stub-axles or on said truck-axle.
10. 3. In a truck attachment for seeders, the combination of a hopper frame members upon which said hopper is mounted, ground-wheels, journals for said ground-wheels longitudinally disposed relative to the hopper, a truck- 15 axle mounted in a transverse position relative to said hopper and intermediate its ends, said truck-axle having a downwardly-bent middle portion secured to said frame members and journal portions at opposite ends thereof and 20 above the plane of the bent portion adapted to receive said ground-wheels, a tongue arranged for attachment to one of said longitudinally-disposed wheel-journals, and means for connecting said tongue with said frame.
25. 4. In a truck attachment for seeders, the combination of a hopper mounted upon frame members arranged longitudinally thereof, ground-wheels, journals for said ground-wheels longitudinally disposed relative to the 30 hopper, a truck-axle mounted in a transverse position relative to said hopper and intermediate its ends, said truck-axle having a downwardly-bent middle portion secured to said frame members and journal portions at 35 opposite ends thereof and above the plane of said bent portion adapted to receive said ground-wheels, a bracket secured to said hopper and provided with a forwardly-projecting tubular portion, a tongue, a draft-piece secured to said tongue and adapted to receive either said tubular portion of said bracket or one of the journals for the ground-wheels.
40. 5. In a truck attachment for seeders, the combination of a hopper, a frame comprising two longitudinally-arranged frame members upon which said hopper is mounted, ground-wheels, journals for said ground-wheels longitudinally disposed relative to the hopper, a bracket secured to said frame members, a 45 truck-axle having a downwardly-bent middle portion embraced by said bracket in a transverse position relative to the hopper and intermediate its ends, said truck-axle being provided with journal portions at opposite ends thereof and above the plane of said bent portion adapted to receive said ground-wheels, a tongue arranged for attachment to one of said wheel-journals, and means for connecting said tongue with said frame. 55
6. In a truck attachment for seeders, the combination of a hopper, a frame comprising two longitudinally-arranged frame members upon which said hopper is mounted, ground-wheels, journals for said ground-wheels longitudinally disposed relative to the hopper, a 60 depending bracket secured to said frame members, said bracket having depending sides, a truck-axle mounted in said bracket in a transverse position relative to the hopper intermediate its ends and embraced by the sides of 65 said bracket, said truck-axle being provided with journal portions adapted to receive said ground-wheels, a tongue arranged for attachment to one of said wheel-journals, and means for connecting said tongue with said frame. 70
7. In a truck attachment for seeders, the combination of a hopper, a frame comprising two longitudinally-arranged frame members upon which said hopper is mounted, ground-wheels, journals for said ground-wheels longitudinally disposed relative to the hopper, a depending bracket secured transversely to 75 said frame members by means of upstanding ear portions, said bracket having depending sides, a truck-axle having a downwardly-depending bent portion embraced by the sides of 80 said bracket and secured therein by a bolt passing through openings in said sides and below said axle, said truck-axle being provided with journal portions adapted to receive 85 said ground-wheels, a tongue arranged for attachment to one of said wheel-journals, and means for connecting said tongue with said frame. 90
- In witness whereof I hereto affix my signature in presence of two witnesses.
